ATTORNEY.

UNITED STATES PATENT OFFICE

HOWARD W. LINKERT, OF INDIANAPOLIS, INDIANA, ASSIGNOR TO THE WHEELER-SCHEBLER CARBURETOR CO., OF INDIANAPOLIS, INDIANA, A CORPORATION OF INDIANA

CARBURETOR

Application filed August 23, 1924. Serial No. 733,695.

In carburetors using liquid fuel, part of the atomized fuel is deposited as a liquid on the walls of the carburetor and the surfaces of any obstructions which may be in the delivery passage of the carburetor. This deposited liquid runs down and collects in an increasing quantity as long as the air velocity through the carburetor is below that value which will cause the collected liquid fuel to be swept into the motor. If, after a considerable collection of liquid fuel has formed, the air velocity through the carburetor is increased sufficiently, this collected fuel is swept on into the motor in addition to the regular supply of fuel, thus temporarily causing an excessively rich mixture, which interferes with the proper action of the motor and produces an uneven rolling action frequently described as "loading". In addition, if the air velocity through the carburetor is not increased, the collection of liquid fuel continues until its amount hinders the regular action of the carburetor and gives an intermittently rich mixture with consequent ill effects.

The principal object of the present invention is to reduce this collection of liquid fuel in the body of the carburetor to a minimum under all operating conditions, especially in the carburetor invented by Berry and Linkert and shown in their application Serial No. 639,191, filed May 15, 1923. Further objects are to reintroduce the collected liquid fuel into the stream of fuel supplied by the metering device to the carburetor nozzle, and into the middle rather than the outside of the air stream through the carburetor, so that it will be least apt to strike the carburetor walls again; to do this by gravity, plus a positive air-pressure and air flow; and to provide an air-bleeding arrangement for the fuel nozzle to promote atomization.

In carrying out my invention, I provide a fuel-returning conduit from the lowest point of the carburetor body, to the fuel passage for a fuel nozzle, desirably into the supply passage for the main fuel nozzle between the metering point and the discharge end of the nozzle. The liquid fuel which is deposited upon surfaces within the carburetor flows by gravity to the lowest portion of said car-

buretor body when the air velocity is low. The fuel thus collected does not remain as a pool at any time, but passes through the fuel-returning conduit into the nozzle, whence it is re-discharged into the air stream. The fuel nozzle discharges within the usual venturi, so that the pressure is lower at the nozzle than in the carburetor body; and this differential air-pressure tends to force the liquid from the lowest point of the carburetor body into the nozzle and thence into the air stream. This same differential air-pressure causes air to be fed into the fuel stream, which air assists in the atomization of the fuel as it is discharged from the nozzle within the venturi and also assist in carrying deposited fuel into the fuel stream.

Although my invention is applicable to carburetors of various designs, it is of especial value as an improvement on the aforesaid carburetor invented by Berry and Linkert, in connection with which carburetor my invention is shown in the accompanying drawing, as that illustrates my invention in the preferred form. In this carburetor, it is most important to prevent the collection of deposited liquid fuel under all conditions, and to insure as thorough atomization of the fuel as possible.

The accompanying drawing illustrates my invention: Fig. 1 is a vertical central section, substantially on the line 1-1 of Fig. 2, through a carburetor embodying my invention; Fig. 2 is a vertical section on the line 2-2 of Fig. 1; Fig. 3 is an enlarged fragmental view corresponding to the lower left-hand part of Fig. 1, showing the fuel control, fuel-return, and fuel-discharge mechanism, being taken substantially on the line 3-3 of Fig. 4; and Fig. 4 is a transverse section, still further enlarged, on the line 4-4 of Fig. 3.

In the carburetor which I have shown, the main body 10 of the carburetor has within it a main chamber 11, into which a venturi 12 projects upwardly, desirably in line with the carburetor-discharge opening 13. The discharge end of a fuel nozzle 15 is located in the vicinity of the choke of the venturi 12. The venturi 12 receives primary air through the primary air inlet 14. Secondary air is ad-

mitted into the chamber 11 through a secondary-air opening 16, the effective size of which is controlled by a spring-loaded secondary-air valve 17. Movements of this secondary-air valve are controlled by the mechanism in a dash-pot 18. This dash-pot mechanism is explained in detail in the aforesaid Berry and Linkert application.

The action of the dash-pot mechanism is such that piston 49, check disc 45, and the disc 46 act together as a solid piston in the cylinder 52, damping out all fluttering, when the air-valve 17 is subjected to slight downward impulses, which occur, for instance, when the carburetor is delivering with a wide-open throttle to a motor running at low speeds. Liquid fuel in the float chamber 25 covers the top of the piston 49 at all times and fills the cylinder 52. The piston 49 is slidably mounted on the stem 50, and the check disc 45 is rigidly fastened to the stem. Under a strong impulse upon the air-valve 17, such as occurs when the throttle is suddenly opened while the motor is idling at a high speed, the spring 48, which is strong enough to withstand a slight pressure, collapses, allowing the liquid in the cylinder 52 to rush rapidly through the holes 47 in the piston 49, and thus permitting the air-valve to drop rapidly to its working position. The disc 46 tends to prevent any downward motion of the air-valve; but allows upward motion thereof, since it drops down to allow liquid to pass through the holes 47 in the piston 49 and check disc 45 into the cylinder 52.

The carburetor-discharge opening 13 is controlled by the usual throttle 19. This throttle is shown connected by a linkage 53 to a fuel-lifting device 20 which is also described in detail in said Berry and Linkert application. The fuel-lifting device provides accelerating fuel when the throttle is opened, by lifting fuel from the cylinder 54, through the restricted passageway 55, into a measuring chamber 56, whence it flows through a metering passageway 58 to the venturi 12. The measuring chamber 56 is provided with an overflow passage 57. The fuel-lifting device gets its supply of fuel from the float chamber 25, into which the lower end of the cylinder 54 opens. The fuel from the float chamber flows upward through openings in the piston of the fuel-lifting device, past a valve disk which rests on the upper face of the piston and which is light enough to be lifted by the head of liquid in the float chamber to uncover the openings in the piston.

Fuel for the fuel nozzle 15 is supplied from the usual fuel chamber 25, the inlet to which is controlled by any suitable float-operated valve 26. The lower end of a tube 27 opens downwardly into this fuel chamber 25, while the upper end of such tube is located within the chamber 11. At an intermediate interior

point, near its lower end, the tube 27 is provided with a valve seat 28, with which the tapered lower end of a fuel-controlling needle 29 cooperates and forms the fuel-metering point of the carburetor. The tube 27 serves as a guide for the needle 29. The fuel-controlling needle 29 is connected to the air-valve 17 by means of a proportioning lever 30, which is pivotally connected to the air-valve 17, the needle 29, and the lower end of the fulcrum lever 56, so that the fuel-controlling needle 29 receives a variably proportionate amount of the movement of the air-valve 17.

The features which so far have been specifically described are all shown in the aforesaid co-pending Berry and Linkert application.

The tube 27 is located within a well 35 formed in the body 10 of the carburetor, at one side of the primary-air-inlet passage 14; but it does not fill such well, so that between the inner wall of such well and the outer wall of the tube 27 there is an annular space 36. Transverse holes 37 in the tube 27 just above the valve seat 28 connect the space within such tube 27 to the annular space 36 around such tube. A transverse passage 38 leads from the annular space 36 to the bottom of the fuel nozzle 15. The passage 38 is conveniently made by drilling through from the outside of the member in which such passage is formed, and then closing the outer end of such passage by an expanding cap, which may be soldered in place. The lower end of the tube 27 has a screw-mounting 39 in the floor of the well 35. The tube 27 is turned bodily in the well 35, by a suitable operating mechanism 40 acting on the upper end of such tube, to adjust the valve seat 28 vertically. The adjusting mechanism here consists of a transverse rotatable member having on its outer end a knurled head to permit it to be manipulated, and having on its inner end a worm which co-operates with worm-wheel teeth on the upper end of the tube 27; so that by turning the knurled head the tube 27 is turned in its screw mounting to be raised or lowered as a result of such turning. This feature is described in detail in the aforesaid Berry and Linkert application.

The upper end of the well 35 opens into the chamber 11 at the lowest point of the floor 41 of such chamber, desirably within a sump 44; and the upper end of the tube 27 projects upward out of the upper end of the well 35. Near its upper end, the tube 27 is guided in its movements in the well 35 by longitudinal ribs 42, provided externally on such tube in the upper end of the well and having between them longitudinal slots 43 which provide communication from the chamber 11 into the annular space 36.

In operation, liquid fuel is deposited on the exposed surfaces within the carburetor, as has already been explained. When the air veloc-

ity through the carburetor is less than a certain value, this liquid fuel flows down by gravity into the cup or sump 44 provided in the floor 41 of the chamber 11, and constituting the lowest point of such chamber 11; from the bottom of which sump the well 35 opens downwardly. This liquid fuel which thus flows into the sump 44 flows down through the slots 43 into the space 36, where it joins the 10 incoming fuel which has just entered such annular space 36 through the openings 37; and this mixture of incoming and returned fuel is fed by the passageway 38 into the nozzle 15, and thence discharged within the venturi 12 into the center of the air stream passing upward through such venturi. In this way, the returned fuel is re-introduced into the air stream, and this re-introduction is into the interior rather than on the outside of 20 such air stream.

The return of this fuel into the main fuel stream is caused not only by gravity, but by a positive differential air pressure between the sump 44 and the discharge end of the nozzle 15, there being an air flow produced by such differential air pressure from the sump 44 through the slots 43, annular passage 36, and transverse passage 38, into the fuel nozzle. This differential air pressure is the bulk of the 30 difference between the pressure in the chamber 11 and the lowered pressure at the choke of the venturi 12, and insures the flow of the fuel from the sump 44 into the annular space 36 and thence into and from the nozzle 15, 35 and the air flow produced by this differential pressure assists in thus moving this returned fuel. Moreover, this air flow produces an air-bleeding into the fuel stream in the nozzle 15, which air-bleeding assists materially in the atomizing of the fuel discharged from such nozzle. This air-bleeding, with its assistance to atomization, may occur at all air velocities; but the return of fuel by the sump 44 and slots 43 into the annular space 36 only 45 occurs when the air velocities are below a certain value. By this return of fuel when the air velocities are low, the formation of a pool of liquid fuel in the chamber 11 is avoided, so that there is no such collection of fuel 50 to be carried over into the motor when an increase in air velocity occurs. Thus the so-called "loading" of the motor by the carburetor is effectively avoided.

I claim as my invention:

55 1. In a carburetor, the combination of a venturi, a fuel nozzle arranged to discharge within said venturi, a well open at its top into said carburetor at a low point in the floor thereof and on the discharge side of the venturi and communicating with said fuel nozzle, a fuel-supply chamber, a tube located in said well but spaced from the walls thereof, the interior of said tube communicating with said well, said tube being provided with a 60 metering communication with said fuel-sup-

ply chamber, the upper end of said well being arranged to receive liquid which is deposited on surfaces within the carburetor beyond the contraction of the venturi.

65 2. In a carburetor, a mixing chamber having a sump, a well open to said sump to receive drainage therefrom, a fuel chamber with which said well also communicates, a fuel nozzle arranged to discharge within said mixing chamber and receiving its fuel from the fuel chamber through said well, and a metering pin controlling passage of fuel from the fuel chamber to said well.

In witness whereof, I have hereunto set my hand at Indianapolis, Indiana, this 15th day of August, A. D. one thousand nine hundred and twenty-four.

HOWARD W. LINKERT.
